UNITED STATES PATENT OFFICE.

JOSEPH B. TIFFANY, OF NEW YORK, N. Y.

GAS-REGULATOR.

SPECIFICATION forming part of Letters Patent No. 233,048, dated October 5, 1880.

Application filed January 12, 1880.

To all whom it may concern:

Be it known that I, JOSEPH B. TIFFANY, of the city, county, and State of New York, have invented certain new and useful Improvements 5 in Gas-Regulators, of which the following is a full, clear, and exact description, reference being had to the accompanying drawings, in which—

Figure 1 is a vertical section of the regulator through the horizontal inlet and outlet pipes. Fig. 2 is a vertical section of the valve-seat. Fig. 3 is a side view of the nut K. Fig. 4 shows two inlet and two outlet pipes.

Like letters indicate like parts in all the 15 figures.

My improvement consists in so constructing the valve and its adjacent parts as to avoid the possibility of the gas being entirely shut off, either by the diaphragm falling onto the 20 valve-hole from above or the valve closing tight up against its seat from below, which often happens in regulators heretofore made, either on account of a decrease or increase in the pressure of the gas, in either of which 25 events the gas has been extinguished at the burners, and then when the flow of gas recommences through the regulator, by the rising of the diaphragm from off the valve-hole or the dropping of the valve out of its seat, the 30 burners have leaked gas. I prevent the diaphragm from falling onto the valve-hole by providing several (three or more) small studs or projections, located adjacent to the valve-seat on the upper side of the upper plate of 35 the inlet-box, as seen at d d, Fig. 1, or on the upper side of the bottom of the regulator-case, and adjacent to the valve, if the valve be located there. These studs may be placed on the under side of the diaphragm. These studs 40 or projections must be sufficiently high to support the diaphragm above and away from the valve, so that the valve-opening will not be closed, and so that there will always be a space between the diaphragm and valve, through 45 which the gas can pass to the outlet-pipe; and I prevent the valve from shutting off the flow of gas by closing tight up against its seat by cutting small slots or grooves in the side of the valve or in the valve-seat, as may be preferred, through which sufficient gas can pass to 50 preserve the flame at the burners, even though

the valve should shut up close against its seat. These grooves or leak-passages are shown at x, Fig. 2. In the seat, and also in the valve, there may, if desired, be more than one of 55 these grooves, and instead of a groove there may be a small hole made directly through the valve. By these means the gas cannot be completely shut off by any variation in the pressure. These leak-passages, however, 60 should not be so large as to interfere with the regulating action of the valve, but merely sufficient to allow gas enough to pass the valve to preserve the flame at the burners, which will depend upon the pressure and the number of burners. These grooves or holes can 65 equally well be made in the old form of valve to effect the object above specified.

I also provide one or more openings or passages from the inside of the regulator-case, 70 above the diaphragm, to the external air, through which the air can freely and readily pass, as shown at E, Fig. 1. I prefer to place this independent air-passage on the side of the regulator and to cover it with a hood or shield, 75 to prevent dust from entering through it and falling on the diaphragm; but the dropping of dirt, &c., on the diaphragm may be avoided by an internal casing covering this independent air-hole e, (seen at e'), and this hole may 80 be made through the case at any point above the diaphragm. The diaphragm is made much more sensitive by the use of these air-passages.

My improvements consist, secondly, in forming small burrs or lugs on the under side of 85 the nut K, Fig. 1, (also seen enlarged in Fig. 3,) which lugs prevent the flat-under surface of this nut from coming down onto the upper surface of the top of the regulator-case, and always keeps these two surfaces apart. I do 90 this because it often happens that this nut, if allowed to come into contact with the case, will stick to it and prevent the action of the regulator, because of an adhesive deposit of a tar-like nature, which comes from the gas. 95 These teats may be placed on the upper surface of the case in such position that they will support the nut K, instead of being attached to the under surface of the nut. These lugs on the nut come only into play when the nut 100 happens to be so adjusted that it strikes the top of the case before the diaphragm is stop-

ped by the lugs *d d*, as may sometimes happen. Under such adjustment the nut will prevent the diaphragm from closing the valve-hole; but I do not depend on the nut for this function, because it might easily get displaced. Hence the provision of lugs *d d* to prevent the descent of the diaphragm beyond a given point is important. This is especially the case when a regulator once used has been laid aside for awhile, or when the gas has been shut off from a house for any considerable length of time and the regulator unused, the balance-weights on the spindle meantime pressing this nut down onto the top of the regulator.

I am aware that a gas-regulator valve allowing some gas to leak through it when closed is known; also, that lugs projecting up from the valve-seat of a gas-regulator to prevent the diaphragm from closing the valve-opening are known. I do not, therefore, claim these features separately.

Having thus described my improvements, what I claim is—

1. The combination, in a gas-regulator, of a valve provided with a leak passage or passages

so formed that the valve when tightly closed cannot entirely shut off the flow of gas, a stem, a diaphragm, supports to prevent the diaphragm from falling on the valve-hole, and an independent air-passage connecting the external air with the space above the diaphragm, substantially as and for the purposes set forth. 30

2. The combination, in a gas-regulator, of a valve provided with a leak passage or passages, so formed that the valve when tightly closed 35 cannot entirely shut off the flow of gas, a stem, a diaphragm, and supports to prevent the diaphragm from falling on the valve-hole, substantially as and for the purposes set forth.

3. The combination, in a gas-regulator, of a 40 valve, a valve-stem, a diaphragm, and nut *K*, the nut being provided with one or more lugs on its underside, as and for the purpose set forth.

In testimony whereof I have hereunto set my hand this 9th day of January, 1880, in the 45 presence of two subscribing witnesses.

JOSEPH B. TIFFANY.
